UNITED STATES PATENT OFFICE.

ALBERT F. VAUGHAN, OF WARWICK, RHODE ISLAND, ASSIGNOR TO THE R. L. GRIFFITH & SON COMPANY, OF PROVIDENCE, RHODE ISLAND.

DESIGN FOR A RING, PIN, OR BROOCH.

49,234.

Specification for Design.

Patented June 20, 1916.

Application filed March 24, 1916. Serial No. 86,516. Term of patent 3½ years.

To all whom it may concern:

Be it known that I, ALBERT F. VAUGHAN, a citizen of the United States, residing at Warwick, in the county of Kent and State of Rhode Island, have invented a new, original, and ornamental Design for Rings, Pins, or Brooches, of which the following is a specification, reference being had to the accompanying drawings, forming part thereof.

Figure 1 is a front view of the ring, pin

or brooch showing my design. Fig. 2 is an edge view of the same.

I claim—

The ornamental design for a ring, pin or brooch, as shown.

ALBERT F. VAUGHAN.

Witnesses:

ADA E. HAGERTY,

J. A. MILLER.
